UNITED STATES PATENT OFFICE

EPHRAIM L. PRATT, OF PHILADELPHIA, PENNSYLVANIA.

MACHINE FOR SLICING APPLES.

Specification of Letters Patent No. 16,067, dated November 11, 1856.

To all whom it may concern:

Be it known that I, EPHRAIM L. PRATT, of the city and county of Philadelphia and State of Pennsylvania, have invented a new and useful Machine for Slicing Apples; and I do hereby declare that the following is a full, clear, and exact description thereof, reference being had to the annexed drawings, making part of this specification.

10 Figure 1 is a front elevation of the machine in the act of slicing an apple. Fig. 2, is a top view of ditto with the apple removed therefrom. Fig. 3, is an end elevation of ditto.

15 Similar letters in the figures refer to corresponding parts.

The nature of this invention consists in cutting apples into slices of uniform thickness by causing revolving knives to alternately pass through the same on lines parallel with the core of the apple as the portion to be cut off is brought forward at intervals in its revolution, in such a manner as to enable the whole apple to be cut into 25 straight slices clear from the core part, by the simple turning of a crank and the operation of such parts as cause the knives to pass the apple in straight lines during their revolutions.

30 To enable others skilled in the art to make and used my invention I will proceed to describe its construction and operation.

The frame A may be made of cast metal or other suitable material, and is provided 35 with projections B, and a clamp screw B', for securing the same to a table or other support. On top of the frame is secured a horizontal shaft C, turning in suitable bearings in the frame and having a crank 40 D, at its outer end and a cog wheel E, at its inner end which cog wheel E meshes in gear with a corresponding cog wheel E, turning on a shaft secured to the upright portion of the frame immediately below 45 the shaft C. This last mentioned cog wheel F, meshes in gear with another cog wheel G, below turning on a shaft fixed to the frame and having a rim H, cast or secured on its face, which rim has two spiral lips 50 I, projecting from its face, next the periphery, and arranged at equal distances apart and which mesh in gear with and act upon the cogs of a horizontal wheel K, secured to the lower end of a vertical shaft 55 supported by and turning in a portion of the frame, and having forks or prongs M,

formed on or secured to its upper end, on which the core part of the apple to be sliced is pressed and secured. The spiral lips or cams I, act upon the cogs of the wheel K, 60 alternately, after the manner of ordinary worm gearing and when they, in their revolutions have turned the cog wheel K, the required distance for a slice to be taken off the apple, the circular portion of the rim 65 H, between the spiral lips or cams I, holds the same firmly during the said cutting process, until the other lip or cam, reaches the next cog in succession.

On the front part of the frame A, is secured a curved bar N, closely resembling in form a skeleton heart, except in the particulars that a portion of its tapered part near the point is slightly curved inward from the ordinary full bulge as at N', and the blunt end is made straight, to correspond with the upright and straight edge of a bar O, secured to the same about two and a half inches to the right hand, by curved bars N'. The upper and lower ends of this vertical 80 bar O, are curved toward the heart formed bar N, to enable the knife guides V, hereafter mentioned, to readily assume their proper positions over and under the same, in their revolutions.

Immediately in front of the heart formed bar N, is arranged, on edge, an oblong plate P, having the ends of parallel rods or bars Q jointed on its outer part, which rods, or bars are jointed at their opposite ends to the lower ends of other rods or bars Q. Secured at their opposite end to a plate S, fixed permanently to the horizontal shaft C, immediately outside the plate P. This plate S, is also of an oblong form, and is arranged 90 parallel to the plate P, to which it is secured, as just mentioned, by the rods or bars R, and parallel connecting rods or bars Q, so as to enable the two plates to be revolved together with the horizontal crank shaft, 95 and the plate P, to have a reciprocating movement on the jointed rods Q, during its revolution, through the action of the outer edge of the heart shaped bar N, on studs or pins T, projecting from the inner face 100 of the plate P, and the action of the straight edge of the bar O, upon the knife guides U—the peculiar form and proportion of the said heart shaped bar N, being such, and the several curved and straight edges of the 110 same being in such relation to each other and to the horizontal shaft C, as to cause

the two studs or pins T, to bear at all times against its edges and thus properly guide the plate P, and prevent it from wobbling. A slot (represented by dotted lines in Fig. 5 1) is formed in the plate P, through which the horizontal shaft C, passes for enabling the said plate to have the reciprocating movement described. At the ends of the plate P, are arranged guides U, secured to 10 pins or studs U', turning in openings in the ends of the plate P, which pins or studs have knives V, secured to near their centers. These knives project inward from the ends of the plate P, at right angles to its inner 15 face, or they may be slightly curved as desired, and are of sufficient length to slice the largest sized apple, being bent at their inner end, in a curved line, corresponding with the arc of a circle scribed from the center of 20 the shaft s so as to separate the inner part of the slice from the core of the apple, immediately outside the said core. The guides U, move over the right hand edge of the bar O, and this bar being arranged parallel 25 with the center of the apple, causes the knives V, to pass through the same on corresponding straight lines.

The operation is as follows: The core of the apple being pressed upon the upright 30 forks or prongs M, as represented in Fig. 1, the operator, sitting in front of the machine turns the crank D, to the right. The studs or pins T, on the inner face of the plate P, moving over the curved edges of the 35 heart shaped bar N, cause the said plate P, to be moved on its jointed bars Q, so as to alternately bring the knife guides U, on its ends, at every revolution in such relation to the curved top part of the upright bar O, as 40 to cause them to go over the top of the same, the slightly curved inward portions of the heart shaped bar N, enabling them to properly assume their parallel positions in relation to, and against the right hand 45 edge of said upright bar. The guide bars U, are then slid downward, in a straight

line being held in contact with this edge, until they reach the same horizontal plane as the center of the horizontal shaft C, by the portion of the lower curved edge of the heart shaped bar, between the slightly curved inward portion N and the extreme left, or point of the same—the plate P, moving on its bars Q to admit of this movement. After the guide bars U, pass the horizontal 50 plane mentioned, they continue their descent with the knives in the same straight course, the action of the edge of the upright bar O, upon them moving the plate P, on its rods Q, to the right, until the knife 55 guides pass under the curved end of the bar O, when the action of the curved edges of the heart shaped bar N upon the studs or pins T, bring the next guide bar U, in its revolution, to the proper position to pass 60 over the upper curved end of the said upright bar O. During the descent of each knife, a slice is cut from the apple, and between the time of one knife leaving the lower end of the upright bar O, and the 65 other knife reaching the top of the same, the apple is revolved sufficiently by the spiral lips or cams I, acting on the cogs of the wheel K, to bring another portion of the same around, to be sliced by the descending knife, while it is held firmly by the circular portion of the rim H between the cogs of said wheel K.

What I claim as my invention and desire to secure by Letters Patent is—

Attaching the knives to a reciprocating piece P by means of pins or axis on which they can so rotate in combination with the straight rod or guide O for the purpose of causing the knives to descend through the 85 apple—in lines parallel to its axis as herein substantially set forth.

E. L. PRATT.
